Specification of Letters Patent.

Patented Oct. 1, 1912.

Application filed April 25, 1912. Serial No. 693,097.

To all whom it may concern:

Be it known that I, FRANS E. FORSELL, a citizen of the United States, residing at Attleboro, in the county of Bristol and State of Massachusetts, have invented certain new and useful Improvements in Bracelets, of which the following is a specification.

My invention relates to that class of bracelets which comprises a plurality of units arranged in expandible relation to each other.

The essential objects of my invention are to avoid the necessity in the construction of the frames, of the use of rivets to unite the parts thereof, thus avoiding the disfiguring and weakening effects of solder and facilitating the construction of the frame; also to provide a means for facilitating the introduction of the links of the bracelet within the frames; to permit the use of an inferior metal in the construction of the frames, if so desired, by a means for concealing the exposed longitudinal portions of the frames; and to facilitate and simplify the construction and the operation of the entire bracelet.

To the above ends essentially my invention consists in such parts and combinations of parts as fall within the scope of the appended claims.

In the accompanying drawings which form a part of this specification, Figures 1 and 2 are edge and side elevations, respectively, of a bracelet embodying my invention, Figs. 3 and 4, sections on line $x-x$ of Fig. 1, showing the parts in closed and exposed positions, respectively, Figs. 5 and 6, edge and back elevations, respectively of one of the frames, Figs. 7 and 8, sections respectively on line $y-y$ of Fig. 5 and $z-z$ of Fig. 3, Figs. 9 and 10, edge and end elevations, respectively, of one of the central links, and Figs. 11 and 12, similar elevations, respectively, of one of the caps.

Like reference characters indicate like parts throughout the views.

My invention comprises interengaging central links A and outer link members B, both of which are of arcuate and oblong general formation. Each central link A has curved front and back walls a and end walls a' . Attached to the inner faces of the end walls a' in any convenient manner, or integral therewith at each end of the link, are plates a'' of greater length than the breadth of the walls a , forming projections a'' extending from both sides of the central link.

Both the tops and bottoms of each link A are open, and within each link are two springs C. Connecting the links A in each case is a frame D. In detail, each frame D, as best shown in Figs. 5 to 7 inclusive, comprises substantially flat, longitudinally disposed plates d , provided with inwardly directed marginal flanges d' said longitudinal plates being integral with flat end bars d'' . One of the plates d is preferably slit or severed at an intermediate portion, such as d'' , the purpose of this slit being to permit the insertion within the frame of the links A during the assemblage of the parts; a construction which among other things avoids the necessity of the use of riveted end posts in the frame and rollers upon such riveted posts, as well as enabling the frame to be struck up in a single piece in a facile and inexpensive manner. After the admission into the frame D of the adjacent central links A, caps E comprising a body portion e and marginal flanges e' are applied to the opposite plates d and d' , whereby the slit d'' is concealed as well also as the base metal 80 of the frame D whenever it is desired to employ base metal for this purpose.

The springs C each have one end pressing against one of the plates a'' in the end of the link A, and its opposite end resting against the flat bar d'' of the frame D. The projections a'' upon the plates and the ends of the links A register in the channels formed by the inturned flanges d' in the longitudinal plates d of the frame D, and thus assist the guiding of the links relatively to each other.

What I claim is,

1. A bracelet comprising links, frames engaging the links and comprising longitudinal plates provided with inwardly directed guide flanges and integral end bars, springs within the links and abutting against the bars and the adjacent ends of said links, said links being open at opposite sides and removable means covering said frames.

2. A bracelet comprising links, frames engaging the links and comprising longitudinal plates provided with inwardly directed guide flanges and integral end bars, springs within the links and abutting against the bars and the adjacent ends of said links, said links being open at opposite sides and one of said plates being severed at an intermediate portion, and flanged caps applied to said plates and covering the slit.

3. In a bracelet, the combination of links, frames engaging the links and comprising longitudinal plates with integral end bars, each link having an end wall, plates attached to the inner faces of said end walls and of greater length than the breadth of said walls, springs within the frame and confined between the ends of the links and the end bars of the frame, the plates of the frame having inwardly extended marginal

flanges one of which is slit, and flanged caps engaging the opposite portions of said plates and concealing said slit.

In testimony whereof I have affixed my signature in presence of two witnesses.

FRANS E. FORSELL.

Witnesses:
